UNITED STATES PATENT OFFICE.

ROBERT C. STUBBS, OF DALLAS, TEXAS; MARIE M. STUBBS EXECUTRIX OF SAID ROBERT C. STUBBS, DECEASED.

SELF-ADJUSTING AND SELF-ADVANCING ROLLER FOR FINISHING CONCRETE AND THE LIKE.

Application filed June 20, 1924, Serial No. 721,253. Renewed October 22, 1927.

My invention relates to rollers for finishing concrete and the like and for removing the surplus mortar or moisture; and the object is to provide rollers for finishing concrete surfaces and which serve as straight edges for making the surfaces even and smooth. Another object is to provide rollers which will be automatically adjusted for advancing by friction against the surface and the amount of the advancing may be predetermined so that the advance will be uniform. The object is to prevent dips or corrugations in the surface and this object is accomplished by making the rollers run at angles over the surfaces. Another object is to provide rollers which are particularly adaptable for use on vibrolithic paving. Other objects and advantages will be fully explained in the following description and the invention will be more particularly pointed out in the claims.

Reference is had to the accompanying drawings which form a part of this application.

Fig. 1 is a plan view of the general form of the roller and the means for operating the roller. Fig. 2 is a similar view, showing one roller running in a position fixed as to the frame and one roller which changes position in operation. Fig. 3 is a plan view, showing two fixed rollers. Fig. 4 is a plan view, illustrating a variation in the frame for operating the self-advancing roller. Fig. 5 is a side elevation of a frame, showing the slots in the frame for movement of the rollers. Fig. 6 is a plan view, showing two self-advancing rollers in one frame. Fig. 7 is a broken side elevation of a frame member, such as shown in Fig. 1. Fig. 8 is a plan view, showing a variation in the manner of adjusting and operating the advancing roller. Fig. 9 is a front elevation of the adjustable roller. Fig. 10 is a side elevation of the device as shown in Fig. 1, provided with an adjustable handle. Fig. 11 is a side elevation of a jointed frame, showing the devices which permit a flexing of the frame. Fig. 12 is a plan view of the same.

Similar characters of reference are used to indicate the same parts throughout the several views.

The principal feature of this invention is a self-advancing roller 1. A frame, having draft or push bars 2 and 3, and side beams

4, is provided for operating the roller or rollers. The roller carrying frame may be operated from either one of the draft members 2 and 3 by means of a handle in two parts. The handle is composed of members 5 which are fixed to the frame and an extensible member 6 which may be long enough to move the frame from one side of the street or road to the other. A clamp 7 may be carried by the members 5 which is adapted to engage the handle 6 at any required point. The clamp 7 may be released from the handle 6 so that the handle 6 may be moved the required distance and then the clamp 7 may be secured to the handle.

The roller 1 may be pivoted to one member of the frame 4 at 8. The roller is mounted on a shaft 9 which is pivotally connected to the frame 4 at 8. The other end of the shaft 9 is slidably mounted in a slot 10 in the frame 4. The connection of the shaft of the roller 1 to frame member 4 may be any suitable swivel connection. In operation, if the frame is moved in the direction of the draft member 2, the roller 1 will drop back to the dotted outline position 11. When the frame starts back to the other side or starting point, the roller 1 will drop back to the dotted outline position 12. The frame members 4 have series of holes vertically therethrough and pins 13 are inserted in these holes to limit the movement or swing of the roller 1. The roller will advance more or less in making the trip across the street according to the position of the pins 13. The swinging of the roller in this manner automatically advances the device on the street.

The moving of the roller angularly across the street paving incidentally accomplishes another function and that is, the preventing of the roller from making creases or corrugations in the paving. If the roller should run directly across the street and back over the same track, there would be a tendency to make creases or corrugations and each time the roller should go back over the same track, the corrugations would be made deeper and in this manner would make a rough street. With the provision for permitting the roller to change directions, the roller will run angularly relative to the previously made impression and thus tend to smooth out any depression previously made.

The roller frame is provided with a han-

dle 6 which should be relatively long because the smoothing device must be moved entirely across the street and back and some streets and roads will be wider than others. 5 The fixed member 5 is provided with a clamp 7 which can be loosened for adjustment of the handle 6.

Additional rollers 15 may be journaled in the frame members 4 for operating on the 10 surface of concrete or other paving. The advantage of the additional rollers is that the additional rollers run directly across the surface and the swinging roller will run at an angle to the other roller or rollers and so 15 smooth out any depression or cavity that other rollers might make.

Fig. 4 of the drawings shows a variation in the means for operating the roller, consisting of a combined yoke and frame 16, and 20 a handle 17.

Fig. 5 shows a frame for the rollers, having a jointed member 18 which is a frame member pivotally connected to the other frame member. The object is to adapt the 25 smoothing device to conform to the curvature of the street.

Fig. 6 shows two pivoted rollers instead of one roller. The rollers operate in the same manner as the one roller above described.

Fig. 8 shows two rollers journaled in the frame members 4 and one roller 19. The roller 19 is journaled in a yoke 20 and the yoke 20 is pivotally connected to a frame 35 member 21. The roller 19 may be set at whatever angle that may be desirable in operation.

Figs. 11 and 12 illustrate smoothing or 40 finishing devices provided with jointed frame members. The side beams are made into two parts and the two parts are connected so that the frame will be flexible. A cleat 22 is pivotally connected to both members of the frame and a cleat 23 is pivotally connected to both members of the side beams. The cleat 23 has slots 24 in each end for the pivot bolts 25.

One of the advantages of this invention 50 is that it provides means for contacting with the surface of the concrete at different angles so that there will be pressure on the surface from several different directions as the roller is moved back and forth across the street or road and the device will be automatically 55 advanced along the street uniformly. This provision will avoid the errors that might be made by careless operators.

What I claim is—

1. A concrete finishing device comprising

a frame and a roller pivotally connected to one side of said frame and slidably connected to the other side whereby said roller is adapted to run at an angle to said frame and to the line of the road or street and to change the angle thereof automatically when the 65 draft is reversed.

2. A concrete finishing device comprising a frame having its side members slotted and roller having a swivel connection with one of said members and having the other end slidably connected to the other one of said members for automatic adjustment of said rollers to the required angle.

3. A concrete finishing device comprising a frame having draft members and slotted 75 side members and a roller having at one end a swivel connection with one of said side members and having the other end slidably connected to the other side member for automatic adjustment of said rollers to the required angle.

4. A concrete finishing device comprising a frame provided with slotted side members and a roller pivotally connected to one of said side members and having the other end 80 slidably connected to the other side member for automatic adjustment of said rollers to the required angle and means for limiting the amount of movement of the slidable end of said roller relative to the frame.

5. A device for acting on the surface of concrete for straightening the surface and for removing surplus material therefrom comprising a frame having one slotted side member and a roller having one end operatively connected therewith and the other end 85 pivotally connected to the other side of said frame and adapted to change automatically its angles relative to said frame and to the street or road when the draft is reversed.

6. A device for acting on the surface of concrete for removing surplus material therefrom and making a smooth finish comprising a frame provided with one slotted side member and a roller having one end 100 operatively connected therewith and the other end pivotally connected to the other side of said frame and adapted to change its angle automatically with the frame at each reversal of the frame to pass from one 110 side of the street to the other for pressing on the concrete from different angles and for automatically advancing the device uniformly along the street.

In testimony whereof, I set my hand, this 115 22nd day of April, 1924.

ROBERT C. STUBBS.
